INVENTOR.

BY *Franck Bizzarro*
ATTORNEY
Robert Greenman

UNITED STATES PATENT OFFICE.

FRANK BIZZARRO, OF NEW YORK, N. Y., ASSIGNOR TO EVERKLEEN SPARK PLUG CORPORATION, OF NEW YORK, N. Y., A CORPORATION OF DELAWARE.

SPARK PLUG.

Application filed August 24, 1927. Serial No. 215,151.

This invention relates to spark plugs with particular reference to such as are used for igniting gaseous fuel in internal combustion engines as employed in motor cars, etc., the same being partly a continuation and partly improvements on applications filed by Frank Bizzarro on November 26, 1923, Serial No. 676,978.

Such plugs have been, in the past, made of substantially unitary construction so that after functioning for a while, they would accumulate a deposit of carbon reducing their efficiency.

In order to remove the carbon, it was necessary to either dismantle the plug entirely or, at least, disengage the plug from the cylinder head.

Another disadvantage of existing devices of this type is that there is no external, visible means to indicate that the plug is not functioning in a proper manner, so that if the engine was not running as it should, it was difficult to locate the fault.

It is therefore the main object of this invention to provide a plug of the character described in which the body is made of sections permitting ready dismantling to permit internal cleaning.

A further object is in the provision of a double-ended reversible electrode, withdrawable as a unit from the plug without disengaging the latter from the cylinder head of the motor.

A still further aim is to provide a spark plug so designed as to permit of a minimum amount of carbon accumulating around the electrodes.

Another feature is to provide means whereby the gap between the electrodes may be readily adjusted to meet varied conditions.

These several objects are attained by the novel construction, combination and arrangement of parts hereinafter described and illustrated in the accompanying drawing, forming a material portion of this disclosure and in which:—

Fig. 1, is a side elevational view of the plug made in accordance with this invention.

Fig. 2, is a vertical sectional view taken approximately through the center line of the same.

Fig. 3, is a fragmentary side elevational view showing a modification of the electrode carrying cap as secured to the body.

In the drawing, the numeral 5 generally designates a chambered body having threads 6 near its lower end by which the same is engageable in the cylinder head of a conventional internal combustion engine.

The body is provided with a seat lined with a rubber gasket 7, on which rests the shoulder 8 of a porcelain insulator 9, held in the body by a clamping nut 10, contacting with a second rubber gasket 11, on the upper surface of the shoulder 8.

Mounted in the top of the insulator 9 is a metal brushing 12, moulded into the insulator and into which is threaded a socket 13 provided with a knurled head, 14, above which is an integral, threaded stem 15, engageable with a binding nut 16.

The lower converged end of the insulator 9 has moulded therein a second smaller metallic brushing 17, and passing through an axial bore in the insulator, is an electrode 18 having terminals 19 and screw threaded portions 20 intermediate the terminals engageable in the socket 13 and bushing 17, the electrode being held rigidly by engagement of a small recess 21, adjacent the inner ends of the threaded portion 20, with a pin 22 fixed on the lower end of a spring strip 23 fixed to the socket 13.

The lower end of the body 5 is provided with a reduced annular band 24, engaging a ring 25, formed on a cap 26 provided with diametrically opposite openings 27 openly communicating with the combustion chamber of the cylinder, the cap being held in a rigid position by a threaded electrode 28 engaging the band 24 and ring 25 and having a terminal 29 formed on its inner end spaced from the terminal 19 forming a slight gap 25 therebetween.

The central portion of the body 5 is provided with oppositely disposed, transverse cylindrical recesses 30 in which are fixed bushings 31 carrying glass rod windows 32 equal in thickness to the walls of the body.

In the modification shown in Fig. 3, the lower end of the body 5 is provided with a plurality of L-shaped recesses 33 receptive of mating elements 34 formed on a cap having an opening 36 similar to the openings 27

one of the elements 34 carrying the electrode 28.

Thus should the engine be functioning improperly, the plugs may be readily inspected 5 by looking through the windows, 32 where, if the plugs are working as they should, the reflection of the spark should be seen.

If no spark is noticed, by removing the electrode 28, the cap may be removed and 10 the terminals 19 and 29 cleaned as well as the surrounding walls of the body 5.

If the electrode 19 should be worn, the same may be removed from the insulator 9 by rotating the knurled head 14 and after 15 total withdrawal from the insulator, the electrode may be reversed to present the other terminal 19 at its outer end.

From the foregoing it will be seen that 20 the several parts are demountable to enable ready cleaning, should the plug be functioning improperly.

It will also be noted that the electrode is so made that should one of its terminals become 25 worn, it may be entirely removed without disengaging the plug as a whole from the cylinder head and reversed to present a new terminal.

While the above is descriptive of the preferred embodiment of my invention, it is to 30 be understood that minor changes may be made without departing from the spirit and scope of the claims hereto appended.

Having thus described my invention what 35 I claim as new and desire to secure by Letters Patent is:—

1. A spark plug comprising a hollow body, a conical insulator therein, a terminal fixed 40 to extend transversely into said body, a double ended electrode reversibly held in said insulator, and means permitting removal of said electrode from said insulator without dismantling the plug.

2. A spark plug comprising in combination, a chambered body having means for 45 fixed engagement, an insulator removably clamped in said body, a bushing in said insulator, a socket extending axially through said bushing, a reversible electrode adjustably engaged in said socket, a radial electrode entering the chamber in said body adjacent the first named electrode, means in said body permitting sparks to be seen, and means on said socket for engaging a conductor. 55

3. A spark plug comprising in combination a chambered body having a screw threaded hollow base containing openings for visual observation, windows in said openings, an insulator in said body, means for 60 removing said insulator without interfering with said body, a bushing clamped in said insulator, a socket extending axially through said bushing, means for removably engaging said socket in said bushing, means for engaging connections for electric conductors to the extending end of said socket, an electrode having like ends adjustably and reversibly held in said socket, a cap having lateral ports removably engageable with the 65 lower end of said body, and a radial electrode adjustably fixed in the wall of said cap.

4. A spark plug having a reversible electrode removably engaged in the body of the 75 plug, guide sleeves engaging the ends of said electrode, said electrode being provided with small recesses, a spring strip fixed to one of said sleeves, a pin on said strip engaging one of the recesses in said electrode, and a second 80 electrode adjustably arranged transversely to the exposed end of said first electrode.

Signed in the city, county, and State of New York, this 30th day of July, 1927.

FRANK BIZZARRO.
